UNITED STATES PATENT OFFICE.

WALTER H. W. BEECHER, OF OIL CITY, PENNSYLVANIA.

WRENCH.

SPECIFICATION forming part of Letters Patent No. 758,035, dated April 19, 1904.

Application filed March 19, 1902. Serial No. 98,951. (No model.)

To all whom it may concern:

Be it known that I, WALTER H. W. BEECHER, a citizen of the United States, residing at Oil City, in the county of Venango and State of Pennsylvania, have invented certain new and useful Improvements in Wrenches, of which the following is a specification, reference being had therein to the accompanying drawings.

This invention relates to that class of wrenches ordinarily having diverging jaws, one of which is provided with a sliding gripping-piece designed to move toward the narrower part of the space between the jaws when under the wrenching force, thus approaching the opposing jaw to increase the gripping pressure on the object to be turned and to prevent the wrench from slipping. In such devices as heretofore made the gripping force is without positive limit, depending on the resistance of the object to turning, the length of the wrench-handle, and the force applied to it. When the resistance to turning is very great, but must be overcome, the gripping force of such wrenches increases with the force applied to the wrench-handle, and to a degree unnecessary for a firm grip, often becoming destructive to the object by denting, crushing, or bending before the resistance to turning is overcome.

It is an important object of this invention to positively limit the gripping force, irrespective of the turning force and resistance, and to furnish means for limiting the gripping force so as to make it accord to the uses to which the wrench is to be put.

The invention consists in certain features of construction and operation by which the strength of the wrench and its readiness and efficiency in use are improved, and especially any denting, crushing, or bending of the object gripped prevented, as is hereinafter set forth.

In the accompanying drawings is shown a wrench embodying the improvement in its preferred form; but it will be understood that such form may be varied in many details without departing from the essential features of the invention.

In the drawings, Figure 1 is a perspective view of a wrench embodying the invention. Fig. 2 is a similar view with the movable gripping part removed. Fig. 3 is a longitudinal sectional view of a portion of the wrench on line 3 3, Fig. 5. Fig. 4 is a sectional view on line 4 4, Fig. 3. Fig. 5 is a front view of the head of the wrench. Fig. 6 is a perspective view of the gripping or sliding jaw-piece.

Referring to the drawings, C is a handle-lever, and A and B the jaws of the wrench. The operative faces of the jaws are inclined toward each other at any suitable angle, the median line of which may be at any desired angle to the median line of the handle C. The jaws are preferably made of steel, and the jaw A is formed with teeth *a*. Formed longitudinally in the inner face of the jaw B is an undercut recess or groove D, the cross-section of which is preferably the greater part of a circle, as shown in Fig. 5. The sliding gripping-piece is composed of a grip-piece F and a rib G, which is formed with or attached to said piece, is longitudinal to the same, and is of the same cross-section as the groove D. The grip-piece F is mounted on the jaw B to slide inward and outward within certain limits in directions inclined toward and from the opposing jaw and is guided and held in place by the rib G, which has a neat sliding fit in the groove D.

Is an aperture which passes through the jaw B at an angle with the groove D and preferably in a plane that longitudinally bisects said groove. Said aperture is screw-threaded to admit the screw N, which turns into and out from the groove D. To accommodate said screw, the rib G is cut away to leave an opening or recess H, which is large enough to allow slight longitudinal movements to the sliding gripping-piece in directions inclined toward and from the opposing jaw, which movements may be shortened or lengthened by turning said screw. This arrangement prevents the rib G from being disengaged from the groove.

It is evident that shortening the motions of the sliding gripping-piece diminishes the

amount of gripping force possible under any wrenching force that may be applied. Stops for the gripping movement may be formed in several ways, provided they be properly adjustable or adjusted, though it will be understood that some features of the invention are independent of such adjustment. To limit the outward movement of the grip-piece F and determine the normal or initial position 5 of the same, I prefer to use the screw N, which forms an adjustable stop by which the play of the sliding gripping-piece may easily be regulated. The inward movement of the grip-piece F is arrested by a positive stop L on the wrench-body or on the jaw B, situated close to the inner end of the piece when the latter is in its extreme outer position, so as to be within operative stopping distance of 10 the same, the movement of which should be 20 very slight.

The screw is so mounted and related to the other parts that it can be adjusted inward and upward far enough to hold the sliding piece F firmly in its inner position, and the tool can 25 in such case be employed when it is desired to have no outward yielding of the sliding piece. The screw is of such length as to permit it to be used to press the sliding piece into the last point of its inward travel when 30 desired. It will also be seen that by having the adjustable stop arranged as it is—namely, on lines inclined to the travel of the sliding piece—the necessity of entirely withdrawing the 35 screw or adjustable stop when it is desired to detach or remove the sliding piece is avoided.

While the plate F may be caused to drop to its outer position by gravity or may be moved by hand before applying the wrench to its work, it is preferable to provide a 40 spring for this purpose, which is shown at S, fitted in the inner part of the groove D and operates in a well-known manner.

The inner end portion or edge of the piece F is shaped, as shown at f, to conform with 45 the shape of the stop L, such shape of L being the best for strength.

It will be observed that the means for mounting and adjusting the gripping-plate are all within the wrench in such manner as 50 not to form projections or increase its thickness or interfere with its insertion into and use in narrow spaces or confined situations.

It will be understood that many matters of construction herein shown, however suitable 55 or advisable, are not absolutely essential, such as the degree of angle between the jaws, the angle at which the handle stands relative to the jaws, the mode of connecting the jaws and handle, (which may be by forging, casting, 60 welding, or by attachment, fixed, movable or adjustable,) the position of space H, screw N, and of aperture E, and the shape of groove D, rib G, and space H.

In using the wrench a slight movement of the handle will bring the sliding gripping piece to its final holding position with a firm grip on the object to be turned, which grip however, is not increased in force or converted into any destructive pressure by the further movement of the handle. The wrench is 65 released with equal facility by a little movement of the handle in the opposite direction. 70

What I claim is—

1. In a wrench, the combination of the two opposing jaws, a handle for turning the jaws, 75 a gripping-piece mounted on one of said jaws and movable along the same on lines inclined to the opposing jaw, an adjustable stop for said movable gripping-piece mounted in its jaw and adapted, while so mounted, to permit 80 the detachment of the movable gripping-piece and adjustable to either of several active positions to vary the limit of travel of the movable gripping-piece, substantially as set forth.

2. In a wrench, the combination of two opposing jaws, a handle for turning the same, a gripping-piece movably mounted on one of said jaws and having a stop-shoulder situated at an angle to the lines of movement of the gripping-piece, and a stop-screw mounted in 90 the last said jaw and movable longitudinally on lines inclined to the path of the movable gripping-piece, and adapted, while in mounted position, either to stop the sliding piece at one or another point in its path or to permit the 95 detachment of said sliding piece, substantially as set forth.

3. The combination of two opposing jaws, a handle for turning the same, a movable gripping-piece mounted on one of the said jaws, 100 an adjustable stop mounted in the last said jaw and movable on lines inclined to the path of the said sliding piece, and shoulders on the sliding piece, one inside and the other outside of the adjustable stop, substantially as set forth. 105

4. In a wrench, the combination of two opposing jaws, a handle for turning the same, a sliding gripping-piece mounted on one of said jaws, a fixed stop for the inward movement 110 of the sliding gripping-piece, and an adjusting-screw for said gripping-piece mounted in its jaw and adapted, while so mounted, to permit the detachment of the said gripping-piece and adjustable to move said gripping-piece to the fixed stop and there secure it, substantially 115 as set forth.

5. In a wrench, the combination of the two opposing jaws, a handle for the same, a sliding, gripping-piece having a depending rib seated in a groove in one of said jaws and movable longitudinally therein, said rib having a recess H, and an adjustable stop mounted in 120 said jaw and adapted to be adjusted relative to the said notch H to vary the limit of travel of the moving gripping-piece, substantially as 125 set forth.

6. In a wrench, the combination of the two opposing jaws, one of the same being provided with a groove, a handle for turning the jaws, a gripping-piece having a rib seated in the 5 groove in the said jaw and removable longitudinally therefrom, said rib having a recess H, and an adjustable stop mounted in the said jaw and adapted to be adjusted relative to said

notch H to vary the limit of travel of the gripping-piece, substantially as set forth. 10

In testimony whereof I affix my signature in presence of two witnesses.

WALTER H. W. BEECHER.
